Primary Examiner — Sharon S Oum*Assistant Examiner* — Vanessa Martinez(74) *Attorney, Agent, or Firm* — Ferguson Case Orr
Paterson(57) **CLAIM**

The ornamental design for a table lamp as shown and described.

DESCRIPTION

1.1 is a perspective view of the design; **1.2** is a left view thereof; **1.3** is a right view thereof; **1.4** is a front view thereof; **1.5** is a rear view thereof; **1.6** is a bottom view thereof; **1.7** is a top view thereof.

The broken lines illustrate portions of the table lamp that form no part of the claimed design.

The table lamp is shown with a symbolic break in its length. The appearance of any portion of the article between the break lines forms no part of the claimed design.

1 Claim, 7 Drawing Sheets(56)
